United States Patent Office

Des. 218,324

Patented Aug. 11, 1970

218,324

COAT HANGER

Mark O. Uitz, Mountain View, Calif., assignor to F. J. L. Corporation, Palo Alto, Calif., a corporation of California

Filed May 8, 1969, Ser. No. 17,072

Term of patent 14 years

Int. Cl. D6—01

U.S. Cl. D33—8

Fig. 1

Fig. 2

Fig. 3

Fig. 4

Fig. 5

FIG. 1 is an isometric view of a coat hanger showing my new design;

FIG. 2 is a top plan view thereof;

FIG. 3 is a left-hand elevational view thereof as viewed in FIG. 1;

FIG. 4 is a front elevational view thereof; and

FIG. 5 is a bottom plan view thereof.

The side of the coat hook or similar article not shown is a mirror image of the side shown.

I claim:

The ornamental design for a coat hanger, as shown and described.
